UNITED STATES PATENT OFFICE.

WILLIAM H. ROOK, JR., OF AKRON, OHIO.

SEWER-PIPE SECTION FOR SEWER-BUILDING.

1,037,329.

Specification of Letters Patent. Patented Sept. 3, 1912.

Application filed June 7, 1912. Serial No. 702,266.

To all whom it may concern:

Be it known that I, WILLIAM H. ROOK, Jr., a citizen of the United States, residing at Akron, in the county of Summit and State of Ohio, have invented new and useful Improvements in Sewer-Pipe Sections for Sewer-Building, of which the following is a specification.

This invention relates to sewer pipe sections used for building sewers and other tubular conduits, and the object thereof is, broadly speaking, to provide a sewer pipe section with the lateral walls thereof provided with means to permit coadjacently-placed segments to interlock, in such a manner that the contiguous segments may be differently positioned with respect to each other to form sewers of varying diameters.

More specifically, the invention resides in forming a sewer pipe section with one of the lateral walls thereof provided with a longitudinally-extending and laterally-projecting rib and with the opposite lateral wall provided with a groove, both groove and rib preferably formed with their faces in the arcs of circles, the radius of the circle in which the face of the projection is formed being less than the radius of the arc of which the face of the groove forms a portion, so that when the groove of a section is received or is interlocked with the rib of a complementary section, a considerable pivotal movement inwardly and outwardly toward and away from the axial line of the sewer is permitted to enable similar sewer pipe sections constructed in accordance with this invention to be employed for constructing sewers having different diameters.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and modifications can be resorted to which come within the scope of the claims hereunto appended.

In the drawings in which similar reference numerals indicate like parts in the different figures:

Figure 1, is a perspective view of a sewer pipe section embodying this invention; Fig. 2, is a transverse sectional view of a portion

of a sewer constructed of sections similar to the one shown in Fig. 1; and, Fig. 3, is a view similar to Fig. 2 of a sewer having a greater radius than that shown in Fig. 2.

Referring to the drawings in detail, the reference numerals 1 and 2 denote respectively, the inner and outer walls of a section of sewer pipe and preferably united by at least one longitudinally-extending radial web 3. The segment is further provided with lateral walls 4 and 5 which are in turn united by means of a transversely-extending web 6 which also unites with the radial web 3. These walls and webs are all formed simultaneously of the same material to thereby set up an integral structure. The wall 4 is provided with a longitudinally-extending and laterally-projecting rib 7 preferably formed with its outer face in cross section in the arc of a circle, and the lateral wall 5 is formed with a longitudinally-extending centrally-placed groove 8 preferably formed in cross-section in the arc of a circle, the radius of which is greater than the radius of the arc described by the outer face of the projection 7. The inner and outer walls 1 and 2 are preferably parallel and the inner wall is formed upon the arc of a circle approximating the curvature of the interior of a sewer to be constructed from these segments and which it is contemplated, as will hereinafter more fully appear, may be one of a series of sewers of varying diameters within reasonable limits which may be constructed from the same size and shape of segment, so that from a plurality of similar segments, sewers of varying diameters may be constructed without altering or changing the shape of the individual segments for each diameter of sewer, it being understood, of course, that the range of diameter in the sewers which can be constructed from a single size of segment and having the same shape will be confined within reasonable limits.

In constructing a sewer, the sections are assembled around a supporting form with the ribs 7 positioned within the grooves 8 of contiguous sections, and the joints between them filled with a binding element 9 such as cement or mortar. The construction of a sewer using this type of block does not differ materially from the methods employed in ordinarily built up walls, and, of course, the sections will break joints in the usual manner.

When the radius of the interior of the sewer to be constructed is less than the radius of the arc of the inner wall 1 the disposal of the segments will be substantially 5 the same as in Figs. 1 and 2 with the spaces for the binding element wider at the outer face of the sewer. If the sewer to be constructed has a radius greater than the radius 10 of the circle of which the inner wall 1 would form an arc, the sections will be disposed as shown in Fig. 3 with the spaces between coadjacent sections greater at the inner face of the wall of the sewer, thereby permitting the use of the same shaped sections 15 in sewers having different diameters without changing the forms of sections for each diameter of sewer built.

It will be noted that by forming the projections 7 upon the arcs of circles having 20 shorter radii than the radii of the arcs upon which the grooves 8 are constructed provides pivotal joints between coadjacent sections which permit the sections to be shifted or 25 their relative positions changed to accommodate them to sizes of sewers of various diameters without destroying or impairing the interlocking qualities of these sections.

I claim:—

1. A sewer pipe section for the purposes 30 described comprising a body member of burned earthenware and comprising inner and outer parallel curved walls united at their ends by lateral radial walls, one of said lateral walls provided with a longitudinally- 35 extending and laterally-projecting rib, the

lateral face of said rib formed in the arc of a circle in cross section, the opposite lateral wall provided with a longitudinally-extending groove, the face of said groove being formed in the arc of a circle in cross section, 40 the radius of the arc described by said rib being less than the radius of the arc described by said groove, whereby when two sections are laterally juxtaposed with the rib of one section seated within the 45 groove of another section each of said sections is adjustable radially with respect to the other section.

2. A sewer pipe section comprising a hollow body member of vitreous material and 50 comprising inner and outer parallel curved walls united at their ends by lateral radial walls, one of said lateral walls provided with a longitudinally-extending and laterally-projecting rib, the opposite lateral wall 55 provided with a longitudinally-extending recess larger in cross section than said rib, whereby when two sections are laterally juxtaposed with the rib of one section received within the recess of a coadjacent section, each section is adjustable radially with 60 respect to the other section.

In testimony whereof I have hereunto set my hand in presence of two subscribing witnesses.

WILLIAM H. ROOK, JR.
